UNITED STATES PATENT OFFICE.

FOSTER B. MACDONALD, OF HAZELTON, PENNSYLVANIA.

ATTACHMENT FOR DENTAL IMPRESSION-TRAYS.

1,248,690.

Specification of Letters Patent.

Patented Dec. 4, 1917.

Application filed April 7, 1917. Serial No. 160,492.

To all whom it may concern:

Be it known that I, FOSTER B. MACDONALD, a citizen of the United States, residing at Hazelton, in the county of Luzerne 5 and State of Pennsylvania, have invented certain new and useful Improvements in Attachments for Dental Impression-Trays; and I do hereby declare the following to be a full, clear, and exact description of the 10 invention, such as will enable others skilled in the art to which it appertains to make and use the same.

The invention relates to an attachment for dental impression trays.

15 The object of the present invention is to provide a simple, practical and efficient device adapted to be readily applied to dental impression trays and capable of effectually preventing the plaster of Paris, modeling 20 compound or other impression material, in which the impression is made, from entering the throat of the patient.

25 A further object of the invention is to provide a device of this character adapted to equalize the pressure of the impression, prevent buckling, eliminate ridges and enable a more accurate impression to be obtained.

30 Another object of the invention is to provide an attachment equipped with means for adjustably securing it to the handle of a dental impression tray and adapted to permit the latter to be held in the usual manner and to afford the necessary space to 35 enable the operator to press his second finger directly against the impression tray in taking an impression so that the pressure will be directly upward and not lateral.

With these and other objects in view, the 40 invention consists in the construction and novel combination of parts hereinafter fully described, illustrated in the accompanying drawing and pointed out in the claims hereto appended; it being understood that 45 various changes in the form, proportion, size and minor details of construction, within the scope of the claims, may be resorted to without departing from the spirit or sacrificing any of the advantages of the invention.

50 In the drawing:

Figure 1 is a plan view of a dental impression tray provided with an attachment and constructed in accordance with this invention.

55 Fig. 2 is a reverse plan view of the same.

Fig. 3 is a longitudinal sectional view of the tray and the attachment.

Fig. 4 is a transverse sectional view.

Fig. 5 is a detail view of the rear trans- 60 verse plate.

Like numerals of reference designate corresponding parts in the several figures of the drawing.

In the accompanying drawing in which is 65 illustrated the preferred embodiment of the invention, the attachment comprises in its construction a rear transverse plate 1, a supporting spring 2 and an adjustable sleeve 3. The supporting plate, which has oppositely 70 inclined side portions, is approximately inverted V-shaped and it extends across the open back of an impression tray 4 to form a rear wall thereof so as to hold the impression material in the tray while an impression is being made so as to secure a uniform pressure on the impression material and prevent any of the same from entering the throat of the patient. The rear plate, which conforms generally to the configuration of 75 the rear edge of the impression tray and which may be of different sizes and forms to conform to the configuration of the mouth of the patient, is provided at its rear face with spaced vertical sleeves 5 for the reception of upturned terminal portions or arms 6 of a forked rear portion of the spring 2. The spring 2, which is constructed of steel wire or other suitable resilient material, consists of a single piece of the same bent 80 centrally and brought together to form a shank 7 and the side portions of the wire at the inner end of the shank are spread or forked to form the sides or arms 8 which are spaced apart at the central longitudinal portion of the impression tray and which converge at the front portion thereof, as clearly shown in Fig. 2 of the drawing. This provides ample space for the second finger of the operator to press against the bottom of 85 the impression tray and exert a direct upward pressure when making an impression. The rear plate is supported by the resilient sides of the shank and it is provided at 90 opposite sides with forwardly extending or inwardly extending lugs or prongs 9 which are located beneath the impression tray at 95 opposite sides of the rear portion thereof to limit the upward movement of the rear plate and to steady the same and the said 100 springs are adapted to permit the plate to yield and at the same time maintain the up-

105 110

per edge of the plate against the roof of the mouth so that the material will be effectually prevented from entering the throat of the patient. The shank 7 is arranged in 5 an eye or sleeve 10 of a slide 11 arranged on the handle 12 of the impression tray and consisting of a flattened sleeve which is adjustable inwardly and outwardly along the handle to position the plate in proper 10 relation with the impression tray. The slide, which embraces the handle 12, is provided with a plurality of springs 13 preferably formed integral with the slide by partially severing portions of the metal thereof, but 15 they may be constructed in any other desired manner and any number of the springs may be employed, and other means may be substituted for the springs for adjustably securing the slide to the handle of the dental 20 impression tray. The springs frictionally engage the upper face of the handle and maintain the slide in its adjustment.

What is claimed is:

1. An attachment for dental impression 25 trays including a rear transversely disposed plate adapted to extend across the back of a dental impression tray for retaining the impression material therein, said plate being provided at opposite sides with inwardly 30 extending lugs arranged to engage beneath the dental impression tray, and means for yieldably supporting the said plate from the tray whereby the plate is adapted to be held against the roof of the mouth and maintained in such position while an impression 35 is being made.
2. An attachment for dental impression 40 trays including a rear transversely disposed plate adapted to extend across the back of a dental impression tray for retaining the

impression material therein, said plate being provided at opposite sides with inwardly extending lugs arranged to engage beneath the dental impression tray, and means for yieldably supporting the said plate from 45 the tray, said means including a longitudinally disposed spring having a front shank and rearwardly extending spaced side portions connected with the plate, and means for securing the shank to the handle of the 50 tray.

3. An attachment for dental impression trays including a rear plate of substantially V-shape provided at its lower edge with lugs and having sleeves at its rear face, a longitudinal spring having spaced sides exposing the central portion of the lower face of the tray and provided with upturned terminal arms or portions fitted in the said sleeves of the rear plate, and means for securing the 60 spring to the handle of the tray.

4. An attachment for dental impression trays including a rear plate adapted to extend across the back of the tray, a longitudinal spring located beneath the tray and 65 having spaced side portions connected with the rear plate, a slide consisting of a transverse flattened sleeve through which the handle of the tray passes, said slide being provided at its under side with an eye or 70 sleeve receiving the said spring, said slide being also provided at its upper face with a plurality of springs engaging the handle to retain the slide in its adjustment.

In testimony whereof I affix my signature 75 in presence of two witnesses.

FOSTER B. MACDONALD.
